UNITED STATES PATENT OFFICE.

MARION I. RANDALL, OF BELLINGHAM, WASHINGTON.

LAMP-CORD REEL.

1,084,960.

Specification of Letters Patent. Patented Jan. 20, 1914.

Application filed January 28, 1911. Serial No. 605,231.

To all whom it may concern:

Be it known that I, MARION I. RANDALL, a citizen of the United States, residing at Bellingham, in the county of Whatcom and State of Washington, have invented new and useful Improvements in Lamp-Cord Reels, of which the following is a specification.

This invention relates to lamp cord reels. The object of the invention is the provision of a simple, efficient and durable reel of the character described whereby the lamp cord may be lengthened or shortened as desired.

Further objects of the invention will appear as the following specific description is read in connection with the accompanying drawing which forms a part of this application, and in which:

Figure 1 is a side elevation. Fig. 2 is an end elevation with parts broken away. Fig. 3 is a detail longitudinal section.

Referring more particularly to the drawing 1 represents a support of any suitable type from which depend the supporting brackets 2 and 3, the latter being provided with a central aperture to receive the pivoting pintle 4 of the drum shaft and the former being provided with a square slot 5 to receive the square shank 6 of the ratchet shaft. The drum shaft is hollow and has embedded therein the spring operated ratchet shaft 6' which is provided with a notched boss 7 adapted to be engaged by the pivoted pawls 8 so as to lock the drum shaft in operated position. The drum shaft is shown as provided with a plurality of collars 8, 9 and 10, the latter two of which form a winding drum for the lamp cord 11 and the former two of which form a drum for the reception of an operating cord 12 which in this instance is a continua-

tion of the lamp cord which passes through an aperture 13 formed in the collar 9.

The lamp cord has one end passed through the support 1 and passes over a pulley 15 on a tension weight 14 and then around the drum shaft between the collars 9 and 10, through the aperture 13 and then around the drum shaft between the collars 8 and 9. It is attached to the drum shaft intermediate the ends of the drum so as to prevent slipping upon the drums and thereby shortening the weight supporting end. By pulling down upon the lamp the operating cord is unwound and consequently the weight supporting end is also unwound and by giving a slight downward pull upon the lamps and then releasing the same, the drums will be wound up by the tension of the spring. The weight being mounted as shown maintains a constant tension on the cord and causes it to properly wind on the drum.

Having thus described the invention, what is claimed is—

The combination with a support, of a lamp cord reel attached thereto and comprising bearing brackets, a spring retracted drum journaled in said brackets, said drum being divided into sections, a lamp cord extending downwardly from the support and then upwardly to form a loop, it being then wound upon one of the drum sections in one direction and oppositely wound upon the other section and adapted to depend therefrom, and a weight having a roller supported by the loop in the cord.

In testimony whereof I affix my signature in presence of two witnesses.

MARION I. RANDALL.
